US00D954972S

(12) **United States Design Patent** (10) **Patent No.:** **US D954,972 S**
(45) **Date of Patent:** **** Jun. 14, 2022**

(54) **ULTRASOUND PROBE**

(71) Applicant: **BFLY Operations, Inc.**, Guilford, CT (US)

(72) Inventors: **Adam Mekeel Mack**, Half Moon Bay, CA (US); **Ryan Silvestri**, Guilford, CT (US); **Timothy A. Hyde**, Columbia, SC (US); **Neil Ferrier**, Greenville, SC (US); **Kevin Coss**, Irvine, CA (US); **David Elgena**, Orlando, FL (US); **Matthew de Jonge**, Brooklyn, NY (US); **Jaime Scott Zahorian**, Guilford, CT (US); **Karl Thiele**, St. Petersburg, FL (US); **Jason Fischman**, Stamford, CT (US)

(73) Assignee: **BFLY Operations, Inc.**, Guilford, CT (US)

(**) Term: **15 Years**

(21) Appl. No.: **29/740,028**

(22) Filed: **Jun. 30, 2020**

(51) LOC (13) Cl. **24-02**

(52) U.S. Cl.

USPC **D24/187**

(57) **CLAIM**

The ornamental design for an ultrasound probe, as shown and described.

DESCRIPTION

FIG. 1 is a bottom, front, right side perspective view of an ultrasound probe showing our new design;

FIG. 2 is a bottom plan view thereof;

FIG. 3 is a top plan view thereof;

FIG. 4 is a left side elevation view thereof;

FIG. 5 is a front elevation view thereof;

FIG. 6 is a rear elevation view thereof; and,

FIG. 7 is a right side elevation view thereof.

The broken lines in the figures represent portions of the ultrasound probe that form no part of the claimed design.

1 Claim, 2 Drawing Sheets
